UNITED STATES PATENT OFFICE.

CARRIE F. HURST, OF CRESTON, IOWA, ASSIGNOR OF ONE-HALF TO EMMA WHITLATCH, OF CRESTON, IOWA.

GARMENT-HANGER.

SPECIFICATION forming part of Letters Patent No. 736,969, dated August 25, 1903.

Application filed June 15, 1903. Serial No. 161,580. (No model.)

To all whom it may concern:

Be it known that I, CARRIE F. HURST, a citizen of the United States, residing at Creston, in the county of Union and State of Iowa, have 5 invented a new and useful Garment-Hanger, of which the following is a specification.

This invention relates to devices for suspending garments, more particularly ladies' skirts, and has for its object to simplify and 10 improve devices of this character; and the invention consists in certain novel features of construction, as hereinafter shown and described, and specified in the claims.

In the drawings illustrative of the invention, in which corresponding parts are denoted by like designating characters, Figure 1 is a perspective view of the device applied. Figs. 2, 3, and 4 are enlarged sectional details.

20 The improved device consists of a supporting-frame, preferably of a single piece of wire formed with an upper portion 10, provided with a central suspension-loop 11 and depending ends 12 13, spaced apart and terminating in upwardly-turned pointed hooks 14 15. The portions 12 13 are connected near the hooks 14 15 by a brace member 16, formed of a flat tube of sheet metal with the ends attached rigidly by any suitable means to the side members, as shown. By this means a very compact, strong, and yet light and cheaply-constructed device is formed which will efficiently support garments of various kinds, more particularly ladies' skirts, as indicated in Fig. 1, 30 and which may be of any suitable size or in graduated sizes.

The wire employed may be tinned, galvanized, plated, japanned, or otherwise protected or ornamented, as required.

The relatively stiff or rigid brace member 40 by its peculiar construction is an important feature of the invention and adds materially to the efficiency and value of the invention by effectually obviating all danger of collapse or displacement of the parts. 45

Having thus fully described my invention, what I claim is—

1. A garment-hanger comprising an upper member having a central suspension-loop and depending ends terminating in upwardly- 50 turned pointed hooks, and a transverse supporting-bar connecting said depending ends adjacent to said hooks, substantially as described.

2. A garment-hanger comprising a wire 55 frame having a central loop and with depending ends spaced apart and terminating in pointed upturned garment-piercing hooks, and a brace member formed of a flat tubular sheet-metal strip connecting said depending ends near their hooks, substantially as described. 60

In testimony that I claim the foregoing as my own I have hereto affixed my signature in the presence of two witnesses.

CARRIE F. HURST.
